UNITED STATES PATENT OFFICE.

WILLIAM NICHOLAS, OF NEW YORK, N. Y., ASSIGNOR TO PREMIER MACHINE COMPANY,
A CORPORATION OF DELAWARE.

SQUIRT-PREVENTER FOR TYPE-CASTING MACHINES.

1,228,588.

Specification of Letters Patent.

Patented June 5, 1917.

Application filed July 7, 1914. Serial No. 849,527.

To all whom it may concern:

Be it known that I, WILLIAM NICHOLAS, a subject of the King of Great Britain, residing at No. 222 West Twenty-third street, 5 in the city of New York, county and State of New York, have invented certain new and useful Improvements in Squirt-Preventers for Type-Casting Machines, fully described and represented in the following 10 specification and the accompanying drawings, forming a part of the same.

My invention relates to type casting apparatus and more particularly refers to type casting and setting machines having removable matrices operated by automatic means, and has for an object to provide means for stopping the entire mechanism promptly upon the occurrence of what is known as a squirt to those familiar with the art; that 20 is to say, a small jet of liquid metal will be forced into whatever crevice may exist by reason of the matrix plate not sitting properly upon the top surfaces of the mold walls.

Heretofore mechanism for the purpose has 25 been provided which either failed to act with sufficient promptitude or has employed an undesirable multiplicity of parts, and therefore the especial advantage of my improvements will be found in the economy 30 of its construction as well as the simplicity and efficiency thereof.

In the accompanying drawings, Figure 1 is a side elevation of so much of a type casting and setting machine as is necessary to 35 illustrate the application of my preferred embodiment; Fig. 2 is a similar plan; and Fig. 3 is a sectional elevation of matrix plate and centering mechanism.

Referring to the drawings: The frame 1 40 of the type casting machine to which my improvement applies is in its essential features similar to that of the machine illustrated in the joint Patent No. 964,677 granted to William Ackerman and myself; 45 and the casting mechanism there employed, as far as is necessary for the illustrating of my present improvements, is shown here, of which the matrix plate 3 is carried by the usual hinged frame 2 over the opening of 50 the mold 7, over the top of which the under side of the matrix plate is designed to make a tight squirt-proof union, the plate 3 being held in such close fitting relationship with the type mold by means of the center-

ing pin 10 which by entering any one of a 55 series of sockets 5 in the back of the plate 3 properly locates the character face corresponding therewith over the mold. The depth of the matrix locating sockets is predetermined with great particularity with 60 reference to the operation of the pin 10 so that when the pin is forced down upon the matrix plate the latter fits snugly over the top of the mold.

It may frequently occur however that a 65 small particle of type metal or other foreign matter may separate the plate from the top of the mold sufficiently to permit a small sheet of molten metal being cast in the opening thus formed which will produce an imperfect type. When this occurs it is desirable to stop the motor immediately so 70 that the defective type may be removed without proceeding farther with the casting.

The centering pin 10 is suitably mounted 75 in the matrix plate frame 2, in which it is adapted to slide vertically, being normally held above the matrix plate by a spring against the action of which the pin is forced downwardly into the sockets 5 of the matrix 80 plate by action of a sliding block 11 yieldably and slidably mounted in the end of the overhanging arm 12 which is alternately raised and lowered by action of the lifting post 13, which is operated in this manner 85 by suitable connections through a forked lever 13^a to a cam on the driving shaft of the type casting machine. A small pin 11^a projects from the side of the block 11 and slidably fits into a slotted recess in the bearing 90 at the end of said arm 12 to prevent the block from becoming displaced therefrom. The block 11 has an upwardly extending stem which goes through a bearing 11^b conveniently attached to the interior of the 95 lifting arm, between which bearing and the block 11 is a compression spring adapted to hold the block 11 in the normal position shown in Fig. 3. Therefore when the centering pin does not go to the full limit of 100 its downward travel as the lifting post 13 descends, by reason of the matrix plate not resting properly upon the mold, it, the said pin, through the action of the fulcrum lever 14 that is pivotally mounted upon the arm 105 12 causes the vertical rod 15, slidably mounted in the lifting post, to be forced downwardly upon the short lever arm 16

upon the rock shaft 17, suitably mounted in bearings upon the frame of the machine. At the opposite end of the rock shaft 17 (Fig. 2) is the finger 18 the outer end of which is adapted to engage a pin 19 projecting laterally from the upper end of the vertical link 20 which is adapted to slide vertically in a suitable bearing on the framework, and loosely pivoted to the end of a bell lever 21 also mounted upon the frame of the machine. Hence when the shaft 17 is rocked by the action of the vertical rod 15 it in turn lifts the link 20 and rocks the bell lever 21.

15 The bell lever 21 is normally held against the stop pin 23 by action of the spring 22, in such position that the arm 24 thereof is contacting the projecting tail piece of the latch 25, which is held against the lever arm 24 by action of its coil spring 26 as shown in Fig. 2. In the relative position of the parts thus described the hooked end of the latch 25 is in engagement with the square shoulder 29 of the sliding block 28. The horizontal contact rod 30 is slidably mounted in brackets 31 and 31^a and is adapted to be moved into two positions, one of which forces the taper end 34 thereof into contact with the terminals 35 of the motor that actuates the type casting machine which, however, is not shown in the drawings. The rod 30 is held in the position of making contact when the shoulder 29 of the block 28 on said rod is engaged by the hooked end of the latch 25 as described above. But when the bell lever 21 impinges upon the tail of the latch 25 to oscillate that member upon its pivotal bearing, it is thrown out of engagement with the shoulder of the block 28 on the 40 rod 30, whereupon the compression spring coiled about the rod 30 and held between the bracket 31 and the collar 33 pinned to said rod, acts to withdraw the taper end 34 from out of electric contact with the terminals 35, 45 thereby breaking the circuit by which the motor is driven.

Thus when the matrix plate is not allowed to seat itself closely upon the top of the mold member, in the manner described, it imparts 50 considerable rotatable motion to the shaft 17 by reason of the greater length of the finger 18 over the lever 16 and also by reason of the similarly increased length of the actuating arm of the fulcrum lever 14 in comparison with the actuating end of said lever, whereby a slight longitudinal displacement of the centering pin 10 will cause the actuating lever arm 24 to lift the latch 25 in the manner described out of engagement with 55 the block on the horizontal contact rod 30

sufficient to permit that member to be carried out of engagement as described.

At the opposite end of the rod 30 is a thumb lever 36, suitably supported in a bracket attached to the frame of the machine, the upper end of which is adapted to contact the end of the rod, and, upon being manually operated, to force the rod 30 into contact with the terminals 34 sufficiently far to permit the latch 25 again to engage the shoulder of the block 28, thereby holding the contact taper 34 into position to complete the circuit that drives the motor.

Having described my invention, what I claim is:

1. In a type casting and composing machine, a mold and movable matrix thereon; yielding means for locating the matrix to form a metal-tight connection with said mold; means comprising a multiplying lever 80 and slidable rods in connection with said lever; a spring actuated circuit making and breaking device normally held in position to complete or close the circuit that drives the motor; means comprising a latch for holding said circuit making and breaking device in said closed circuit making position; and means connected with one of said rods for operably disconnecting said latch from said circuit closing device. 90

2. In a type casting and composing machine having a mold and a movable matrix plate thereon, yielding means for centering and seating said matrix plate upon said mold to form a metal-tight connection between 95 said mold and plates; means for breaking the current that drives the motor of said machine when said plate has not been seated sufficiently close to said mold to prevent molten metal from entering the crevice formed thereby, comprising a spring yielding contact rod normally held by a spring latch in position to close the motor circuit; and means whereby said latch is lifted to permit said rod to be withdrawn from its contact 100 closing position, comprising a fulcrum lever having a short arm at one end and long arm at the other end; a vertically sliding rod between the short arm and said matrix plate, and a similar rod operably disposed 110 between said long arm and said latch lifting mechanism.

In testimony whereof, I have hereunto set my hand in the presence of two subscribing witnesses.

WILLIAM NICHOLAS.
